Primary Examiner — Jasmine Mlinarcik(74) *Attorney, Agent, or Firm* — Oyen Wiggs Green & Mutala LLP(57) **CLAIM**

The ornamental design for compression shorts, as shown and described.

DESCRIPTION

FIG. 1 is a front elevation view of the compression shorts;

FIG. 2 is a rear perspective view thereof;

FIG. 3 is a right side view thereof;

FIG. 4 is a left side view thereof;

FIG. 5 is a perspective rear bottom view thereof;

FIG. 6 is a perspective bottom view thereof;

FIG. 7 is a laid flat front view thereof; and,

FIG. 8 is a laid flat rear view thereof.

The dot-dot-dash broken lines define the bounds of the claimed design and form no part thereof. The features depicted in all other broken lines form no part of the claimed design.

1 Claim, 8 Drawing Sheets(56)
